TION OF NEW YORK.

CARBURETER.

1,375,898.

Specification of Letters Patent. Patented Apr. 26, 1921.

Application filed September 11, 1918. Serial No. 253,558.

To all whom it may concern:

Be it known that we, ERNEST F. CIGLIA, a subject of the King of Italy, (having declared my intention of becoming a citizen 5 of the United States of America,) and residing at No. 340 West 86th street, in the city and State of New York, and LOUIS F. PELLETIER, a citizen of the United States of America, and residing at No. 302 West 10 111th street, in said city of New York, have invented a new and useful Improvement Carbureters, of which the following is a specification.

The object of our invention is to produce 15 a carbureter, which shall always supply an explosive mixture of fuel and air suitable to the running of the engine with which it is used, which shall require little, if any, adjustment after the initial adjustment, and 20 which shall, at all times, be under control of the person using it.

We will describe a carbureter embodying 25 our invention and then point out its novel features in claims.

In the accompanying drawing illustrating 30 a carbureter embodying our invention, Figure 1 is a plan or top view partly in section. Fig. 2 is a side view partly in section. Fig. 3 is an elevation. Fig. 4 is a longitudinal vertical section on the plane 35 of the dotted line 4—4 included in Fig. 1. Fig. 5 is an irregular transverse vertical section in planes indicated by the dotted line 5—5 included in Fig. 2. Fig. 6 is a perspective view of certain parts for regulating the supply of air and the supply of fuel. Fig. 7 is an elevation of a needle which controls the fuel supply. Fig. 8 is an elevation of this needle at right angles 40 to the elevation of Fig. 7. Fig. 9 is a bottom view of a valve whereby an abnormally rich explosive mixture may be produced. Fig. 10 is a horizontal section taken in the planes indicated by the line 10—10, in Fig. 5. Fig. 45 11 is an enlarged horizontal section of certain parts also shown in Fig. 1 and Fig. 10. Fig. 12 is a horizontal section like Fig. 11, but showing one of the parts in a different position. Similar letters of reference designate corresponding parts in all the figures.

A designates an ordinary chamber containing a float for regulating the supply of liquid fuel, such as gasolene, to the carbureter. From its lower portion extends a conduit *a* through which the fuel may flow 55 from the fuel chamber to a nozzle B, whence the fuel escapes and mixes with air to produce an explosive mixture for use in an internal combustion engine.

The chamber A may be cast with the conduit *a*, and the latter provided with a flange *a'* fitting against a flange *c'* of the shell C of the carbureter. Screws *d* serve to secure together the flanges *a'* and *c'* and so unite the chamber A with the shell C of the carbureter.

Preferably the fuel nozzle B is made of a separate piece fitted in a tubular portion *c²* of the carbureter shell C and secured therein by means of screw threads *c³* which provide for a longitudinal adjustment of the nozzle to vary the protrusion of its tip. The lower end of the nozzle is provided with nicks or notches *c⁴* which may be engaged by an ordinary screw driver to vary the position of the nozzle. To make the use of a screw driver possible, there is below the nozzle in the conduit *a* a screw plug *a²* which may be removed, and which besides providing for the insertion of a screw driver, facilitates the removal of sediment which may lodge in the conduit *a*.

The carbureter shell C comprises a Venturi tube *c⁵* *c⁶* *c⁷* *c⁸*. The section *c⁵* constitutes an air chamber which tapers toward the axis of the throat *c⁶* which is at its inner end. It consequently is constructed to converge the air stream about the axle of said throat and there is the region of the greatest velocity of the air stream. The section *c⁷* flares beyond the throat *c⁶* and with the section *c⁸* constitutes a mixing chamber in which the mixture expands.

It will be seen that the fuel nozzle B protrudes into the throat *c⁶* of the Venturi tube. 95 The suction of the engine will cause the inflow of air through the section *c⁵* of the Venturi tube, thence through the throat *c⁶* and across the end of the fuel nozzle B. The current of air so produced will atomize, 100

take up and mix with itself whatever quantity of fuel is permitted to escape from the fuel nozzle B, and the mixture so formed will, as already indicated, pass away through 5 the section c^8 .

D is an air controlling valve, here shown as consisting of a thin flat plate provided with a circular hole d^{10} , and fitted to the carbureter shell C, so as to be capable of 10 sliding transversely and as here shown vertically, across the throat c^6 of the Venturi tube. The Venturi tube causes the air stream to be converged so that it is directed about the fuel nozzle B to cause a depression 15 about said nozzle and induce flow of fuel. The air valve D controls the air stream and by making this valve in the form of a thin plate, arranging it close to the nozzle and providing it with a round hole opposite the nozzle its efficiency in causing 20 the convergence of the air stream about said nozzle and the carburetion of the air stream is promoted. It will be found convenient to construct the section c^5 of the 25 Venturi tube separately from the throat c^6 and sections c^7 c^8 , and to provide it with a flange or plate c^9 which may be secured by screws c^{10} to the carbureter shell C, and to so construct and combine it with the latter 30 as to form therewith a slide-way c^{12} for the air controlling valve D.

It will be obvious that by moving the air controlling valve D in different directions, its hole d^{10} may be made to communicate 35 more or less extensively with the throat c^6 of the Venturi tube, and thus increase or decrease the quantity of air passing through the section c^5 of the Venturi tube suitably to the needs of the engine from time to time.

40 To provide for varying the supply of fuel suitably for different conditions of engine service, we provide a fuel valve, and prefer to make this in the form of a needle E. This needle tapers downwardly at its operative end, so that by moving it more or less into the fuel nozzle it will decrease or increase 45 the quantity of fuel permitted to pass from the latter into the Venturi tube.

50 Preferably this needle will taper only in two opposite planes or flat portions e like a wedge instead of having a conical taper. A glance at Figs. 7 and 8 will make this construction apparent. The nozzle is internally tapered conically to its tip and 55 made of such size that it can be closed by the circular portion of the needle and more or less opened by the tapered portion of the needle.

It will be seen that the conduit leading 60 to the fuel nozzle and the fuel nozzle, except at its tip, are made quite large to permit a free flow of fuel to the tip and to maintain a large volume of fuel close to the tip. The flat sides of the needle cause 65 the fuel to escape in two approximately flat

streams. Because the needle is tapered only in two opposite planes it is of maximum diameter between these two planes. Consequently it has a bearing throughout the length of the tip portion of the nozzle 70 and is prevented by the latter from any possible deflection which would cause or permit variations in the air stream.

The flat surfaces lie in the plane of the axis of the Venturi tube, hence the two 75 streams will be flattened lengthwise of the Venturi tube. This, we believe, will materially increase the efficiency of the carburetion or mixing of the air and fuel.

A simple way of operating the needle E 80 is to connect it with the air valve D. We have shown the air valve D as having secured to it a block d' . Screws or similar devices may be used to effect the union. The needle E is shown as extending vertically 85 through this block and as clamped in position relatively to the block by screws d^2 which are notched at the outer ends and may be engaged by a screw driver upon the removal of the section c^5 of the Venturi 90 tube with its plate c^9 .

It will be seen (Figs. 4 and 6) that the upper end of the needle E extends above the block d' to facilitate longitudinal adjustment in said block, and that the portion 95 c^{11} of the carbureter shell C is provided with an opening covered by a screw e' having a tubular body into which the needle may rise. This contrivance is adopted to afford convenience in adjusting the needle. 100

From what has been said it will be understood that the air valve D and the fuel needle valve E must move together to simultaneously increase and to simultaneously decrease the quantities of air and fuel passing 105 through the Venturi tube. It is important to arrange them close together as shown and at the throat of the Venturi tube, with the air valve the nearer to the air inlet and with the fuel nozzle protruding 110 into the throat of that tube.

While other means are possible for moving the valves D and E, we have shown a simple combination of parts consisting of a pin and anti-friction roller f' engaging 115 with a transverse notch d^3 formed in the block d' and carried by two arms f^2 extending from a tubular rock shaft f^3 mounted upon an axle f^4 supported in the portion c^{11} of the carbureter shell C. An arm f^5 extends from the tubular rock shaft f^3 and is provided with a pin and anti-friction roller f^6 which engages with a transverse notch in a reciprocating bar f^7 which is supported 120 to slide longitudinally in the carbureter shell C. Motion is imparted to this bar f^7 by an arm f^8 provided with a pin and anti-friction roller f^9 engaging with a transverse notch f^{10} in the bar f^7 , the said arm being affixed to a rock shaft f^{11} mounted in 130

bearings in the carburetor shell C, and having affixed to one end outside of the carburetor shell an arm f^{12} . This arm f^{12} is provided with a number of holes, with any one 5 of which may be engaged a rod comprised in a combination of parts extending within reach of the person controlling the carburetor.

On that portion of the rock shaft f^{11} 10 which passes through the cylindrical outlet c^8 of the Venturi tube we arrange a valve G, here shown as of the type known as a butterfly valve, and secured so that it will oscillate with the rock shaft f^{11} , by means 15 of a screw g engaging with a screw thread in the hub of the valve and entering a recess in the rock shaft. In different positions this valve G will vary the flow of the explosive mixture through the section c^8 of 20 the Venturi tube to the engine always, when open, dividing the mixture into two streams which meet and commingle beyond it, perfecting the homogeneity of the mixture if not already perfect.

25 It will be seen that an oscillatory motion of the arm f^{12} will not only adjust the air and fuel valves D and E, but will additionally adjust the butterfly valve, all simultaneously for the best results as herein- 30 after stated.

It is of great importance not only to regulate according to the exigencies of engine service at different times the air valve and the fuel valve, but also the explosive mixture valve.

35 The shape of the hole d^{10} in the air valve, the degree of taper of the fuel valve, the angle of the mixture controlling valve to the axis of the Venturi tube when said 40 valve is in its closed position and the connections between these three valves cause a more rapid increase of the opening for the fuel nozzle and air chamber than the explosive mixture chamber and this conduces 45 to smoothness in the operation of an engine during starting and while varying its speed.

We believe that the angle of the taper of the section c^7 of the Venturi tube is important and that internally it should be 50 substantially twelve to sixteen degrees to the axis of this section of said tube and preferably fourteen degrees. We prefer to make the angle of the taper of the section c^5 to be from sixteen to twenty degrees, 55 and most preferably eighteen degrees. A straight Venturi tube has advantages over one that is bent or curved and it is important, we believe, to make the throat of a Venturi tube short, by arranging the two 60 reversely tapering portions close together.

Our carburetor comprises other devices designed to provide for an explosive mixture abnormally rich in fuel for use in the engine at certain times, as for instance, 65 when the engine is started. They comprise

a conduit or passage c^{14} which terminates in a valve chamber c^{16} shown as cylindric in form. Ports c^{17} c^{18} extend between this valve chamber and the section c^8 of the Venturi tube. A valve c^{19} of cylindric form 70 is adapted to reciprocate in the valve chamber c^{16} and a bearing c^{31} . It has ports c^{20} c^{21} in its periphery, as shown more particularly in Fig. 9, which communicate with each other, and which are always in communication with the conduit or passage c^{14} . In a certain position illustrated by Figs. 1 and 10 the port c^{20} establishes communication between the conduit or passage c^{14} and the port c^{17} , thus permitting a flow of fuel 75 into the section c^8 of the Venturi tube beyond the butterfly valve G, simultaneously closing the port c^{18} . Thus the starting of the engine with which the carburetor operates will be facilitated. 85

When reciprocated to the other extreme position illustrated in Fig. 11, the valve c^{19} will close the port c^{17} and establish communication between the conduit or passage c^{14} and the port c^{18} , whereupon fuel will be 90 permitted to flow into the section c^8 of the Venturi tube at the other side of the butterfly valve G.

The port c^{21} of the valve c^{19} terminates in a port c^{30} extending longitudinally along 95 the periphery of the valve while gradually decreasing in area. Consequently, if the valve c^{19} is reciprocated gradually toward the first described position, it will gradually reduce the supply of fuel flowing from 100 the conduit or passage c^{14} into the port c^{18} . When the valve c^{19} is moved beyond the first described position and into the position shown in Fig. 12, it will close both 105 ports c^{17} c^{18} , whereupon the fuel can only flow into the Venturi tube under control of the needle valve E.

The valve c^{19} may be reciprocated by a crank arm c^{22} , which is mounted on a rock shaft c^{23} and engages with the valve by 110 means of a pin and anti-friction roller c^{24} , mounted on a crank arm c^{25} affixed to the rock shaft c^{23} and fitting in a notch formed in said valve. The rock shaft c^{23} is supported in a bearing c^{26} formed in the carburetor shell C. 115

The crank arm c^{22} may be connected with a rod extending to a place where it may be easily reached by the person controlling the carburetor. 120

The rock shaft c^{23} is shown as having secured to it a crank arm c^{27} , which cooperates with a detent to hold the rock shaft normally in position, to close the ports c^{17} and c^{18} . As here shown, this detent consists of a ball c^{29} , pressed by a spring c^{28} against a recessed portion of the crank arm c^{27} . 125

These devices for providing an abnormally rich explosive mixture are not here 130

claimed but are reserved for another application which is to be a division of this application.

What we claim, and desire to secure by Letters Patent is:

1. In a carbureter the combination of a Venturi tube constructed to converge an air stream about the axis of its throat, a fuel orifice so arranged that its axis will be transverse to the axis of said Venturi tube, a needle valve for controlling the outflow of fuel through said orifice, a valve fitted to said Venturi tube so as to operate in a plane transverse to the axis of said Venturi tube and in close proximity to said fuel orifice, a valve in the outlet portion of said Venturi tube controlling the outflow of the mixture and means whereby all three of said valves can be operated simultaneously, substantially as specified.
2. In a carbureter the combination of a Venturi tube constructed to converge an air stream about the axis of its throat, a fuel orifice so arranged that its axis will be transverse to the axis of said Venturi tube, a needle valve for controlling the outflow of fuel through said orifice, a valve fitted to said Venturi tube so as to operate in a plane transverse to the axis of said Venturi tube and in close proximity to said fuel orifice, a valve in the outlet portion of said Venturi tube controlling the outflow of the mixture and means whereby all three of said valves can be operated simultaneously and moved positively in both directions substantially as specified.
3. In a carbureter the combination of a Venturi tube having an air chamber constructed to converge an air stream about the axis of its throat and a flaring mixing chamber arranged axially in line therewith and beyond said throat, a fuel orifice so arranged that its axis will be transverse to the axis of said Venturi, a needle valve for controlling the outflow of fuel through said orifice, a valve in the outlet portion of said Venturi tube so as to operate in a plane transverse to the axis of said Venturi tube and in close proximity to said fuel orifice, a valve in the outlet portion of said Venturi tube controlling the outflow of the mixture and means whereby all three of said valves can be operated simultaneously, substantially as specified.
4. In a carbureter the combination of a Venturi tube having an air chamber tapering at an angle of about 18 degrees and constructed to converge an air stream about the axis of its throat, a fuel orifice so arranged that its axis will be transverse to the axis of said Venturi tube, a needle valve for controlling the outflow of fuel through said orifice, a valve fitted to said Venturi tube so as to operate in a plane transverse to the axis of said Venturi tube and in close proximity

to said fuel orifice, a valve in the outlet portion of said Venturi tube controlling the outflow of the mixture and means whereby all three of said valves can be operated simultaneously, substantially as specified.

5. In a carbureter the combination of a Venturi tube having an air chamber and having a mixing chamber flaring at an angle of about 14 degrees, the said air chamber being constructed to converge an air stream about the axis of its throat, a fuel orifice so arranged that its axis will be transverse to the axis of said Venturi tube, a needle valve for controlling the outflow of fuel through said orifice, a valve fitted to said Venturi tube so as to operate in a plane transverse to the axis of said Venturi tube and in close proximity to said fuel orifice, a valve in the outlet portion of said Venturi tube controlling the outflow of the mixture and means whereby all three of said valves can be operated simultaneously, substantially as specified.

6. In a carbureter the combination of a Venturi tube constructed to converge an air stream about the axis of its throat, a fuel orifice so arranged that its axis will be transverse to the axis of said Venturi tube, a needle valve for controlling the outflow of fuel through said orifice, a valve consisting of a plate provided with a round hole and fitted to said Venturi tube so as to operate in a plane transverse to the axis of said Venturi tube and in close proximity to said fuel orifice, a valve in the outlet portion of said Venturi tube controlling the outflow of the mixture and means whereby all three of said valves can be operated simultaneously, substantially as specified.

7. In a carbureter the combination of a Venturi tube, a fuel orifice so arranged that its axis will be transverse to the axis of the Venturi tube, a needle valve for controlling the outflow of fuel through said orifice, a valve fitted to said Venturi tube so as to operate in a plane transverse to the axis of said Venturi tube and in close proximity to said fuel orifice, a valve on the outlet side of said fuel orifice for controlling the outflow of the mixture, all said valves being constructed, positioned and connected so that the said valve for controlling the outflow of the mixture will be opened more slowly than the other said valves, substantially as specified.

8. In a carbureter, in combination, a tubular member comprising an air inlet portion and an outlet portion, the axes of such portions being arranged in a straight line, a fuel orifice positioned intermediate the ends of said member and arranged to discharge fuel into said member transversely to the axis thereof, a needle valve for controlling the outflow of fuel through said nozzle, a valve fitted to said member so as to operate

in a plane transverse to the axis thereof in close proximity to said orifice, the air inlet portion of said tubular member having a bore tapering inwardly to converge an air stream about said orifice, a valve in said outlet portion of said tubular member, and means whereby all three of said valves may be operated simultaneously, substantially as specified.

Signed at the city of New York, in the 10 county of New York and State of New York this 23d day of July, A. D. 1918.
